UNITED STATES PATENT OFFICE

157,877

COMBINATION RANGE

Ralph E. Kruck, Clinton, Conn., assignor to Majestic Manufacturing Company, St. Louis, Mo., a corporation of Missouri

Application October 10, 1949, Serial No. 5,412

Term of patent 14 years

(Cl. D81—4)

To all whom it may concern:

Be it known that the undersigned, Ralph E. Kruck, a citizen of the United States, residing in Clinton, Connecticut, has invented a new, original, and ornamental Design for a Combination Range, of which the following is a specification, reference being had to the accompanying drawing, forming a part thereof, in which:

Fig. 1 is a perspective view of a combination range showing my novel design, the covers being disposed over the heating areas and burners; and

Fig. 2 is a plan view thereof with the covers removed.

The other side which is not shown, is substantially like the side shown.

I claim:

The ornamental design for a combination range, substantially as shown and described.

RALPH E. KRUCK.
